(*) Notice: This patent is subject to a terminal disclaimer.

(57) CLAIM

(**) Term: **14 Years**

The ornamental design for a safety gate, as shown and described.

(21) Appl. No.: **29/160,366**

DESCRIPTION

(22) Filed: **May 10, 2002**

FIG. 1 is a perspective view of the design;

(51) LOC (7) Cl. **25-02**

FIG. 2 is a front view of the design;

(52) U.S. Cl. **D25/50**

FIG. 3 is a rear view of the design;

(58) Field of Search D25/39, 50; 256/73;
49/207, 371

FIG. 4 is a bottom view of the design;

(56) References Cited

FIG. 5 is a top view of the design;

U.S. PATENT DOCUMENTS

FIG. 6 is a left side view of the design; and,

3,290,014 A * 12/1966 Stapleton 256/73

FIG. 7 is a right side view of the design.
